FLYING TOY

Arthur K. Bilder, Chicago, Ill.

Application January 13, 1955, Serial No. 33,960

Term of patent 3½ years

(Cl. D34—15)

Fig. 1

Fig. 3

Fig. 2

Fig. 1 is a perspective view of a flying toy embodying my new design the perspective being taken from below;

Fig. 2 is a side elevational view of the flying toy of Fig. 1; and

Fig. 3 is a top plan view of the flying toy of Fig. 1.

The dominant features of my new design are shown in solid lines in the drawing.

I claim:

The ornamental design for a flying toy, substantially as shown and described.
